REVOLVING SIGN

Morrison C. Treesh, East St. Louis, Ill., assignor
of one-half to Commodore Carr, East St. Louis,
Ill.

Application August 1, 1936, Serial No. 93,892

1 Claim. (Cl. 40—77)

This invention relates to revolving signs. An object is to provide a sign of this character using neon or other types of illumination, the structure being so designed as to conceal the driving mechanism, the transformers, collector rings, etc., so that only the display portion of the sign and the structural features associated therewith are visible to the observer.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

In the accompanying drawings the preferred form of the invention has been shown.

20 In said drawings

Figure 1 is an elevation of a sign embodying the present improvements.

Figure 2 is an enlarged section on line 2—2, Figure 1.

25 Figure 3 is an enlarged section on line 3—3, Figure 2.

Figure 4 is a section through the commutator of the sign.

Referring to the figures by characters of reference 1 designates a suitable supporting member of any desired construction but preferably tubular so as to constitute a conduit through which wires leading to the sign can be extended. In the illustrated structure the member 1 extends into 35 and supports a drum-like unit constituting the body of the sign structure, the same being of any desired configuration. This unit includes hubs 2 and 3 mounted for rotation on the member 1 and provided with anti-friction bearings indicated generally at 4. Arms 5 radiate from the upper hub 2 while other arms 6 radiate from the lower hub 3. The outer ends of the upper arms are joined by a rim 7 preferably flanged as indicated at 8 while the outer ends of the lower arms are 40 connected by a rim 9 having an inwardly extended bottom flange 10. This bottom flange supports plates 11 of any suitable material and configuration.

50 Mounted on and secured to the lower hub 3 is a sleeve 12 supporting a gear housing 13 which is fastened thereto and is formed preferably of upper and lower sections detachably connected as indicated at 14. Housing 13 has an extension 15 in which is journalled the upwardly extending shaft 16 of an electric motor 17. This shaft car-

ries a screw or worm 18 for transmitting motion through the usual worm gear, to a shaft 19. This shaft is journalled within the housing 13 and its extension 15 and carries a gear 20 which constantly meshes with another larger gear 21 located in housing 13 and fixedly secured to the tubular member 1 as shown at 22.

5 Insulating posts 23 and 24 are fixedly mounted on the housing 13 each of which carries brushes as indicated at 25 and 26. These brushes contact with commutators 27 and collector rings 28 insulated from but fixedly secured to member 1. Current is supplied to these elements by wire 29 extending through member 1.

The rims 7 and 9 carry a housing 30 constituting the outer surface of the sign structure and on this housing are arranged the illuminating elements 31 which can be in the form of neon tubes, or any other type of illuminating means. They can be positioned to give any effect found 20 most desirable and have been indicated generally in Figure 1 as forming words, borders, etc. The upper and lower portions of the drum on housing 30 can be stepped as shown at 32 in Figure 1, or any other design of sign can be employed to meet 25 the taste of the user.

Transformers 33 are located at desired points on the plates 11 and are suitably wired to the brushes 25 and 26 and also electrically connected to the illuminating elements 31. Motor 17 is likewise properly connected electrically to the brushes 25 that engage the collector rings 28.

30 It will be apparent that when current is directed into the motor 17, the gear 20 will be driven slowly by the worm gearing indicated generally at 18. As a result this gear 20 will be caused to travel along the fixed gear 21 and as the motor and gear 20 are carried by the rotatably supported portion of the sign, it will be apparent 35 that housing 30 will be caused to rotate slowly about the tubular member. As the brushes 26 electrically connected to the motor are in contact constantly with the collector rings 28 to which the input and output wires 29 are extended, the 40 operation of the motor and of the sign housing or casing 30 will be continuous. The brushes 25 engaging the commutators 27, however, will set up a desired intermittent current to the display members of the sign with the result that these 45 members 31 will be illuminated whenever desired during the rotation of the sign.

50 Importance is attached to the fact that all of the mechanism of the sign is completely housed within the casing or housing 30 so that it is invisible and is fully protected. The sign can be 55

5 mounted in any manner desired and can be rotated about a vertical or a horizontal axis, as will be apparent. As before stated it can be of any configuration preferred and while it is preferred to use neon tubes for the display portions of the sign, it will be obvious that other types of illumination can be employed or the illumination can be eliminated entirely, especially during the daytime.

10 The sign will of course be made weather-tight in any preferred way.

What is claimed is:

15 A rotary sign including a supporting member, upper and lower rotary members thereon each including a hub, radial arms and a rim having an inwardly extended flange, a sleeve secured upon

5 and rotatable with the hub of the lower member, a housing fixed on and rotatable with the sleeve, a gear fixedly secured to the supporting member and positioned within the housing, speed reduction gearing within the housing, a supporting element mounted on the flange of the lower member, a motor mounted thereon, said speed reduction gearing constituting means for transmitting motion from the motor to the gear on the support, a housing surrounding and carried by the 10 upper and lower rotatable members, lamps carried by the housing, and means on the supporting member for distributing electric current to the motor and lamp during the rotation of the flange about the supporting member.

15 MORRISON C. TREESH.
